J. W. Gibbs, of Albany, N. Y.

Assignor to,

Abbott & Lawrence, of Philadelphia, Pa.

Letters Patent No. 1108. Dated June 14, 1859.

The schedule referred to in these Letters Patent, and making part of the same.

To all whom it may concern:

Be it known that J. W. Gibbs in the City of Albany in the County of Albany and the State of New York, have invented or produced a new original ornamental design for the plates of a six plate wood stove, and I do hereby declare the following is a full and exact description thereof, reference being had to the accompanying drawings and to the letters of reference marked thereon.

Fig. 1. represents the back plate of the said six plate wood stove, all ornaments running along the top edge of the said plate, marked A. all claimed as original, as also the ornament B, in the center of, and forming in combination with the moldings C.

an ornamental panel for the said six plate wood stove. The ornamental corners D, in combination with the panel and panel ornament B, are claimed as original.

Fig. 2. represents the side plate of the said six plate wood stove. The ornament E forming the panel together with the ornaments F, running along the top of said side plate and ornamental corner G, also all moldings marked H, are, in combination with the ornaments and moldings of the said back plate of the said stove, claimed as original.

What I claim as my invention or production is the ornamental configuration and combination of ornaments of a six plate wood stove.
